ORNAMENTAL MUSIC TEACHING DEVICE

Robert G. Wyatt, P.O. Box 27, Moose Jaw,
Saskatchewan, Canada

Filed May 6, 1971, Ser. No. 141,102

Claims priority, application Canada Nov. 7, 1970

Term of patent 14 years

Int. Cl. D19—07

U.S. Cl. D25—1

FIG. 1 is a perspective view thereof; and
FIG. 2 is a top plan view thereof.

The opposite side not shown in the drawings is plain and unornamented, the rear leg not seen is identical to those shown in FIG. 1.

I claim:

The ornamental design for an ornamental music teaching device, substantially as shown and described.
